[57] CLAIM

The ornamental design for a pavement marker, as shown and described.

DESCRIPTION

FIG. 1 is a perspective view of a pavement marker showing my new design;

FIG. 2 is a top plan view thereof;

FIG. 3 is a right side elevational view, with the left side being a mirror image thereof;

FIG. 4 is a front elevational view, with the rear being a mirror image thereof.

The undisclosed bottom is unornamented.

FIG. 1

FIG. 2

FIG. 3

FIG. 4
